[57] CLAIM

The ornamental design for a swivel bath seat for infants,
as shown and described.

DESCRIPTION

FIG. 1 is a perspective view taken from the top, front
and right side of a swivel bath seat for infants showing
our new design;

FIG. 2 is a front elevational view thereof;

FIG. 3 is a left side elevational view thereof, the right
side being a mirror image of the left side;

FIG. 4 is a rear elevational view thereof;

FIG. 5 is a top plan view thereof.

Fig. 1
